US00D702892S

(12) **United States Design Patent**
Duvigneau

(10) **Patent No.:** **US D702,892 S**
(45) **Date of Patent:** **** Apr. 15, 2014**

(54) **COMBINED PET FOOD CONTAINER AND FEEDER BOWLS**

(75) Inventor: **Nikolai Duvigneau**, Zichron Yaakov (IL)

(73) Assignee: **Curver Luxembourg Sarl**, Neidercorn (LU)

(**) Term: **14 Years**

(21) Appl. No.: **29/394,412**

(22) Filed: **Jun. 16, 2011**

(51) **LOC (10) Cl.** **30-03**

(52) **U.S. Cl.**

USPC **D30/121**; D30/129; D30/130; D30/133

(57) **CLAIM**

I claim the ornamental design for a combined pet food container and feeder bowls, as shown and described.

DESCRIPTION

FIG. 1 is a side perspective view of a combined pet food container and feeder bowls shown in an assembled condition; FIG. 2 is a top, front perspective view thereof; FIG. 3 is a top, side perspective view thereof; FIG. 4 is a bottom perspective view thereof; FIG. 5 is a front view of the combined pet food container and feeder bowls, the rear view being identical; FIG. 6 is a side view of the combined pet food container and feeder bowls, the opposite side view being identical; FIG. 7 is a top plan view thereof; FIG. 8 is a bottom view thereof; FIG. 9 is a top, side perspective view of the feeder bowl component, shown alone for clarity of illustration; FIG. 10 is a bottom perspective view thereof; FIG. 11 is a side perspective view thereof; FIG. 12 is a front view thereof; FIG. 13 is a top perspective view thereof; FIG. 14 is a bottom view thereof; FIG. 15 is a top perspective view of the handle component, shown alone for clarity of illustration; FIG. 16 is a bottom perspective view thereof; FIG. 17 is a top view thereof; FIG. 18 is a bottom view thereof; FIG. 19 is a side view of the handle component, the opposite side view being identical; and, FIG. 20 is a bottom, side perspective view thereof.
